CLAIM

The ornamental design for a handheld stabilizer, as shown and described.

DESCRIPTION

FIG. 1 is a perspective view of a handheld stabilizer showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the handheld stabilizer shown in a first configuration of use;

FIG. 10 is a perspective view of the handheld stabilizer shown in a second configuration of use;

FIG. 11 is a perspective view of the handheld stabilizer shown in a third configuration of use;

FIG. 12 is a perspective view of the handheld stabilizer shown in a fourth configuration of use;

FIG. 13 is a perspective view of the handheld stabilizer shown in a fifth configuration of use;

FIG. 14 is an enlarged view of portion 15 shown in FIG. 1; and,

FIG. 15 is an enlarged view of portion 15 shown in FIG. 2. The dash-dash broken lines in the drawings depict portions of the handheld stabilizer that form no part of the claimed design. The dot-dash broken lines represent boundaries of the enlarged portions and form no part of the claimed design.
